UNITED STATES PATENT OFFICE.

DON T. HASTINGS, OF DETROIT, MICHIGAN, ASSIGNOR TO PACKARD MOTOR CAR COMPANY, OF DETROIT, MICHIGAN, A CORPORATION OF MICHIGAN.

DESIGN FOR A HUB-CAP.

46,499.

Specification for Design.

Patented Oct. 6, 1914.

Application filed July 24, 1911. Serial No. 640,363. Term of patent 7 years.

To all whom it may concern:

Be it known that I, DON T. HASTINGS, a citizen of the United States, residing at Detroit, in the county of Wayne and State of Michigan, have invented a new, original, and ornamental Design for Hub-Caps, of which the following is a specification, reference being had to the accompanying drawing, forming part thereof.

The invention relates to hub caps, and has particular reference to the ornamental appearance of those used upon motor vehicles.

In the accompanying drawing: Figure 1 is a top view; and Fig. 2 is a side view.

I claim:

The ornamental design for a hub cap, as shown.

DON T. HASTINGS.
